UNITED STATES PATENT OFFICE.

JOSHUA M. RICHARDS, OF BELMONT, MASSACHUSETTS.

DESIGN FOR SHEET GLASS OR SIMILAR ARTICLE.

Application filed November 9, 1923. Serial No. 7,722. Term of patent 14 years.

To all whom it may concern:

Be it known that I, JOSHUA M. RICHARDS, a citizen of the United States, residing at Belmont, in the county of Middlesex and State of Massachusetts, have invented a new, original, and ornamental Design for Sheet Glass or Similar Article, of which the following is a specification, reference being had to the accompanying drawing, forming part thereof, which is a perspective of the sheet glass or similar article, the dotted lines indicating that the bottom surface of the glass is ornamented with the same series of uniform curvatures as the top surface of the glass, showing my new design.

I claim:

The ornamental design for sheet glass or similar article as shown.

In testimony whereof I have signed my name to this specification.

JOSHUA M. RICHARDS.
